UNITED STATES PATENT OFFICE.

HELON B. MACFARLAND, OF CHICAGO, ILLINOIS.

SHOCK-RECORDING DEVICE.

1,125,145.

Specification of Letters Patent. Patented Jan. 19, 1915.

Application filed January 23, 1914. Serial No. 813,831.

To all whom it may concern:

Be it known that I, HELON B. MACFARLAND, a citizen of the United States, and resident of Chicago, in the county of Cook and State of Illinois, have invented a certain new and useful Improvement in Shock-Recording Devices, of which the following is a description, reference being had to the accompanying drawings, which 10 form a part of my specification.

My invention relates to a device more especially intended for use in connection with railway cars and the like, whereby the shocks encountered by the car or cars may 15 be recorded and the nature or extent of the shock or shocks indicated.

A further object of the invention is the provision of a device whereby the time when the shock or shocks were received will be indicated, in order that the specific time and place, where the car, either by reason of undue handling or otherwise, may have encountered the shock or shocks, may be determined, as will very clearly appear from 25 the following detailed description.

In the drawings:—Figure 1 is a top plan view of my invention arranged in a suitable casing, with the top or cover thereof removed. Fig. 2 is a side elevation of the 30 same, a side of the casing being removed, and a portion of the casing for the time or record-sheet operating mechanism broken away in order to show the operative connection between said mechanism and the record-sheet holding cylinder or member. Fig. 3 is a vertical sectional view taken on the line 3—3 of Fig. 1, looking in the direction of the arrows. Fig. 4 is a detailed sectional view taken on the line 4—4 of Fig. 3, 35 looking in the direction of the arrows. Fig. 5 is a vertical sectional view taken on the line 5—5 of Fig. 4, as indicated by the arrows.

In the particular exemplification of my 40 invention, as disclosed in the drawings, the device is arranged to be affected by and to record the shocks which may be encountered by the car and are imparted thereto in a direction parallel with the longitudinal axis 45 of the device. As most of the damage, both to the car and to its contents, is usually incurred through shocks caused by impact at the ends of the car, and, therefore, shocks transmitted in a direction extending longitudinally of the car, my improved device is

intended to be arranged parallel with the longitudinal center line of the car; the device being so arranged that it will not interfere with the interior or capacity of the car, and at the same time so that its proper operation may not be hindered by the car-contents and yet permit of proper observation thereof; the intent being also to so incase or house the device that injury or undue tampering therewith may be prevented. 60

I have illustrated the device inclosed in a proper casing or compartment A, which may be independent of the car-body, or be made a part thereof, and so arranged that access to the device may be readily had for 70 the purpose of noting the result of its operation, or for the purpose of setting or repairing the device.

In the specific embodiment of my invention as shown, the device comprises suitable 75 standards as shown at 10, 10, arranged a sufficient distance apart and properly secured in the casing or compartment A by means of the bolts 11, see Fig. 2. The standards 10, 10 are adapted to receive the 80 longitudinal rod or shaft 12, which is preferably maintained against either longitudinal or rotative movement by any suitable means, such as the set screws 13, which extend through the top of the pillow-blocks 85 or standards 10, 10, as very clearly shown in Figs. 1 and 2. The rod or shaft 12 may be of any suitable form or shape, being preferably shown rectangular in cross-section, as can more clearly be seen in Figs. 90 3 and 5.

The rod or shaft 12 is provided with a weighted member or block 14 of any suitable construction, arranged so as to permit it to slide freely along the rod or shaft 12. 95 In order to permit of the free movement of member 14, lengthwise of rod or shaft 12, the opening through the member 14 may be made larger than the diameter of rod or shaft 12, and thus enable suitable anti-friction means being inserted or provided intermediate of the bearing surfaces of the block or member 14, and the rod or shaft 12. In the construction as illustrated in the drawings, I have shown the member 100 105 or block 14 provided with a sufficiently large opening extending therethrough in order that the weighted member or block 14 may receive the sleeve or channel member 15 provided with a sufficient number 110

of anti-friction members or rollers 16 properly journaled therein against longitudinal movement but free to revolve, as very clearly shown in Figs. 4 and 5. The sleeve 5 or member 15 is so constructed that its displacement or longitudinal movement in the opening of member 14 will be prevented, as is clearly apparent from Fig. 4. The rollers 16 bear on the top surface of the rod 10 or shaft 12 and permit the weighted member 14 to easily slide along the rod or shaft 12. It is evident, however, that the anti-friction bearing between the weighted member 14 and the shaft or rod 12 may be differently provided; the object of the construction illustrated being to eliminate any friction that might be encountered between the member 14 and the rod or shaft 12, and hinder the free sliding movement of the 20 former along the latter.

Intermediate of the ends of the rod or shaft 12, and therefore intermediate of the pillow-blocks or standards 10 and the opposite sides of block or member 14, I provide 25 resilient controlling means which is illustrated in the nature of coil springs 17, 17, encircling the rod or shaft 12 so as to be maintained in proper alignment. It is apparent from the construction that the force 30 or tension of one spring will be in direct alignment with the force or tension of the other and an equal amount of resistance offered member 14 to its free movement toward either end of the shaft 12. The 35 springs 17, 17, are preferably of the same length and strength so that the member or block 14 will normally be maintained at and returned to a prearranged point or zero position; the nature of the springs being such, however, that the weighted member 40 14, when subject to abnormal conditions, will readily compress the springs and thus provide a vibratory movement or tendency.

The weighted member or block 14 is provided with a suitable arm or extension 18, which may either be made integral therewith, or secured thereto as in the construction illustrated by means of suitable screws 19. The outer end of the arm or extension 50 18 is arranged to receive a suitable stylus or record-inducing member 20, preferably in the nature of a pencil which may be secured in a suitable threaded sleeve 21 which screws into the threaded opening in the end 55 of arm or member 18. In order that the stylus or pencil may adjust itself to slight jars, and at the same time be maintained in operative contact with the record strip or cylinder, the pencil may be provided with 60 a flange or collar 22 and a spring 23 arranged intermediate of flange 22 and the lower end of sleeve 21, as very clearly shown in Figs. 2 and 3.

A record-receiving sheet or strip is arranged so as to be in contact with the point

of the pencil 20; and this record-sheet or strip may be provided with lines or suitable indicia which may determine not only the nature of the impact or shock recorded thereon, but also the time when the same 70 was received.

It is evident, therefore, that the record-sheet or strip should have movement in a direction transversely of the movement of the pencil; this movement may be either a 75 continuous or an intermittent one, induced by any suitable clock or other operating mechanism.

I have chosen to illustrate this part of the invention in the nature of a suitable 80 cylinder 24, mounted on the end of a shaft 25, which has its bearing in the standard 26. The end of the cylinder 24 or the shaft 25, is provided with a pinion 27 which meshes with a pinion 28 mounted on a shaft 85 29, which latter has its bearing in a standard 26.

The end of shaft 29 is provided with a spiral gear 30, see Figs. 1 and 2, which meshes with a worm gear 31 mounted on 90 a shaft provided with the pinion 32 which is driven by the pinion 33 of ordinary clock mechanism, mounted in the casing B. The pinion 32 is shown meshing with the spring gear 33 of clock mechanism and controls 95 the operation of said mechanism when the usual spring is wound up by means of the winding key 34. As ordinary clock mechanism is employed, a detailed description of this part of the device need not be entered into.

The cylinder 24 is so constructed as to permit a record-sheet 35 to be readily placed thereon; for example, the cylinder 24 may be provided with a longitudinal slot 24^a 100 adapted to receive the ends of the sheet 35 and thereby maintain the sheet in place.

The operation of the specific form of my improved device, as shown in the drawings, is as follows:—The device is arranged at a 110 suitable point within the car, or a suitable compartment thereof, and placed so that the slide-rod or shaft 12 extends in the direction of the impacts to which the car may be subjected and which it is intended to record. The record-sheet holding cylinder is of such 115 length that it may receive a sheet or strip of paper of a width commensurate with the maximum degree of movement of member 14 that may be induced through severe 120 shocks or impacts imparted to the car. The record-receiving sheet may be provided with any suitable indicia to denote time as well as the degree of impact recorded thereon; it being understood, of course, that the record-sheet or strip is provided with a normal or zero point at which the record-inducing means, namely the stylus or pencil 20, will rest during the normal condition of the device. The record-sheet or strip is moved 125

transversely across the direction of movement that may be imparted to the pencil or recording means, by the gradual, continuous movement of the pinions which are operated, in the particular exemplification, by means of the clock mechanism, so that a different portion of the record-sheet or strip will be periodically brought into contact with the pencil or record-inducing means.

It is evident that any shocks transmitted in a direction longitudinally of rod or shaft 12 will cause the pencil 20, by means of member 14 sliding along rod or shaft 12, to move across the record-sheet 35 secured about cylinder 24, causing an indicating line or mark to be made on the sheet to opposite sides of the zero point, as is indicated in Fig. 2; the length of the mark indicating the degree of force or nature of the impact; while the point where the indicating line or mark is made, with reference to the direction in which the record-sheet is moving, will indicate the time when the shock was received.

My invention is especially adapted for use in connection with either freight or passenger cars, as it will provide a record of the time as well as the nature of the various shocks, especially those in excess of a predetermined degree, that have been encountered by the car while in transit, thus enabling the proper parties to determine whether or not any claims for breakage or injury to the contents of the car, were the result of improper handling of the car, rather than the improper or careless manner in which the shipment was sent.

It will be understood, of course, that the springs, or other means whereby the record-inducing means is maintained at and returned to normal or zero position, is preferably of such nature that the device will not be too sensitive, but be adapted to merely record shocks in excess of a predetermined degree; and any suitable means may be employed to maintain the proper relation between member 14 and shaft 12, so as to prevent any rotary movement of member 14.

I have shown and described what I believe to be the simplest and best form of my invention, but it is apparent that certain modifications may be employed to produce the same results, without, however, departing from the spirit of my invention, and I do not wish to be understood as limiting

myself to the exact construction shown and described.

What I claim is:—

1. A shock recording device, comprising a slidably mounted member provided with a record inducing portion, said member being adapted to move in a line parallel with the direction of the impact intended to be recorded, means arranged on opposite sides of said member whereby the member is yieldingly maintained at or returned to normal position, and means for receiving a record sheet or strip, said means being arranged in proximity to the record inducing portion of said member and arranged to move the sheet or strip in a direction transversely to the movement of said record inducing portion of the member.

2. A shock recording device, comprising a member slidably mounted and provided with a record inducing portion, spring mechanism arranged on opposite sides of said member and arranged to maintain said member at normal position or return it thereto, a record sheet holding cylinder arranged in proximity to said record inducing portion, and means whereby the cylinder is rotated at predetermined intervals in a direction transversely to the movement of the member.

3. A shock recording device, comprising a supporting shaft or member adapted to be arranged parallel with the direction of the shocks intended to be recorded, a member slidably mounted thereon, said last mentioned member being provided with a record-inducing portion, resilient mechanism arranged on said shaft on opposite sides of and in controlling engagement with said second mentioned member whereby said member may move lengthwise of said shaft or member through shocks imparted thereto and be returned to normal or zero position, a record-receiving member arranged in proximity to the record-inducing portion of the second member, and clock mechanism adapted to give the record-receiving member predetermined movement in a direction transversely to the direction of movement of said second member.
